E. VOGUE

PROPELLER

Filed March 2, 1922

Edward Voge

Paulmin & Paulmin

Attorney

UNITED STATES PATENT OFFICE.

EDWARD VOGE, OF WEST ALEXANDRIA, OHIO.

PROPELLER.

Application filed March 2, 1922. Serial No. 540,621.

To all whom it may concern:

Be it known that I, EDWARD VOGE, a citizen of the United States, residing at West Alexandria, in the county of Preble and State of Ohio, have invented certain new and useful Improvements in Propellers, of which the following is a specification, reference being had therein to the accompanying drawing.

10 My invention relates to propellers and in particular to propellers for aeronautical purposes.

It is an object of my invention to provide a propeller in which the surface can be varied at different positions of the propeller.

15 It is a further object of my invention to provide means of varying the effective area of the propeller as it revolves on its axis.

It is my object to provide a novel mechanical movement by which as the propeller moves as a unit about its main axis a portion thereof will be shifted laterally to expose one portion thereof.

In particular, it is my object to adapt my 25 propeller to airplanes and the like but I do not desire to confine myself to this application as my construction is adaptable to other uses such as stirrers for fluids, etc., where it is desirable to have a stirrer of one 30 area in one portion of the fluid and a stirrer of a different area in another portion of the fluid to set up certain predetermined currents in the fluid mass.

Referring to the drawings:

35 Fig. 1 is an elevation of one side of my propeller;

Fig. 2 is an elevation of the other side of my propeller;

Fig. 3 is a section on the line 3—3 of 40 Fig. 1, looking downwardly;

Fig. 4 is a section on the line 4—4 of Fig. 1, looking downwardly;

Fig. 5 is a section on the line 5—5 of Fig. 1, looking towards the right hand to show 45 the cam mounting for actuating the shutters on my propeller.

In detail, the drawings show a bracket 1 of any suitable character which may be a portion of an airplane, etc., in which is 50 journaled an operating shaft 2. This shaft is also journaled in a diagonal bracket 3 which is mounted on 1 by the studs 4 and 5. The bracket 3 is spaced from 1 at one end by a collar 6. Mounted on 3 is a cam ring 55 7. It is retained on 3 by the bolts 8. A link or rocking arm 9 is pivoted on the

shaft 2 by a pin 10 so that it reciprocates or rocks back and forth about 10 as an axis and at the same time moves bodily with 2 about the major axis of 2 as an axis. At either 60 end of 9 is pivoted a link 11 which is in turn pivoted at 12 to a plurality of shutters 13, consisting of vertical bars or members of any desired configuration, connected together at the ends thereof by cross members 65 14 which are guided by rollers 15 mounted on the propeller frame 16. The propeller frame has a plurality of cut away portions 17 of a width equal to the width of the shutters 13. 70

In the upper part of Fig. 1 it will be seen that the shutters have closed the openings 17 while in the lower part of Fig. 1 these openings have been opened by the shutters 13 being withdrawn. The propeller frame 75 16 is fastened by the pins or any other suitable means designated 18 to the main driving shaft 2 to which the power is applied.

It will be understood that I may employ 80 one or more openings 17 and corresponding shutters 13 and I may employ one or more propellers on the same shaft either located on different portions of the shaft or located on the same shaft depending upon the adaptation I desire to make of my propeller. 85

It will be also understood that the construction is an illustrative one and I do not desire to be confined to the mechanical details, but have simply shown this construction for the purposes of a simple illustration 90 in order that my invention may be readily understood.

As to the operation of my invention, power is ordinarily applied to the shaft 2, 95 although I comprehend within my invention the application of power to the propeller blades and the constant transmission of power to the shaft 2. As the propeller rotates, the openings 17 will be closed on the upstroke and maintained in their closed position a predetermined time and then gradually opened on the downstroke, remaining open a predetermined time until the closing operation takes place again. Simultaneously the shutters on the other 100 end of the propeller open and close at opposite times to the opening and closing of the first mentioned shutters. 105

This results in a variable resistance offered to the fluid medium in which the propeller is traveling to satisfy certain conditions of use. 110

Having thus fully described my invention, what I claim as new and desire to secure by Letters Patent, is:—

1. In combination, a propeller, a shaft upon which the propeller is mounted, an opening in either end of the propeller in the body thereof, a shutter on either end thereof to close said opening, means mounted upon the propeller shaft and rotating therewith to automatically operate the shutter intermittently to opened and closed position at different points in the revolution of the propeller, said operating means being adapted to rotate with said shaft, and means located adjacent the propeller shaft to cause the operating means to rock.
2. In combination, a driving shaft, a propeller mounted thereon, openings in either end of the propeller, shutters therein adapted to be shifted laterally to close the opening, a cam upon the driving shaft, a rock-shaft mounted thereon, and means connecting the rock shaft to the shutters whereby upon the rotation of the propeller shaft the rock shaft will automatically operate the

shutters intermittently to opened and closed positions at different points in the revolution of the propeller.

3. In combination, a propeller, a shaft on which said propeller is mounted, a plurality of openings in either end of said propeller, a plurality of shutters adjacent thereto, means for connecting said shutters to one another and spacing them from one another, guiding means on said propeller adapted to engage said connecting means to guide said shutters adjacent the openings, a link connected to each group of shutters, a rock arm connected to each link at either end thereof, said rock arm being pivoted on the main shaft on which the propeller is mounted, a cam mounted adjacent said rock arm whereby as the propeller rotates the cam will rock the rock arm and the shutters will be actuated to close the openings in either end of the propeller intermittently.

In testimony whereof, I affix my signature.

EDWARD VOGE.
